UNITED STATES PATENT OFFICE

FRITZ STEINECKE, OF SINDELFINGEN NEAR STUTTGART, GERMANY, ASSIGNOR TO
DAIMLER-BENZ AKTIENGESELLSCHAFT, OF STUTTGART-UNTERTURKHEIM, GERMANY, A COMPANY OF GERMANY

ROLLER HOOD FOR POWER DRIVEN VEHICLES

Application filed April 22, 1931, Serial No. 532,089, and in Germany March 14, 1930.

This invention relates to a device for guiding roller hoods and is chiefly useful for all weather motor coaches in which the hood can be slid along guides provided laterally on the roof.

This device according to the invention is so arranged that the shocks reaching the guides from below are not transmitted to the hood. For this purpose the guided members are divided, the member carrying the hood being resiliently connected with the part of the guide which transmits the shocks. In this way breakages of the tilt hoops and the parts of the cover, are avoided. The invention further consists in providing two guiding tracks of which one is arranged above and the other below and a two-part guiding carriage, the two parts being forced in opposite directions against the guiding tracks by means of springs.

A further object of the invention is to press the guiding rollers on to the guiding tracks, so that they cannot rattle, but still can easily be made to slide without exertion.

The invention also provides a three track guide, one guide track having a single track and the other oppositely directed guiding track having a double track so that the guiding carriage can fit the curves of the guide more easily.

This is also to be further improved by the guiding rollers being mounted on their journals loosely with axial play so that at curves they can yield laterally and do not jam.

Furthermore an oblique position of the parts of the guiding carriage and jamming of the same is avoided by the parts being secured from turning relative to one another.

Further a particular advantageous and simple construction protected against dust and the like will be obtained.

A constructional example is illustrated in the accompanying drawings, in which

Fig. 1 shows a motor omnibus with roller hood in elevation,

Fig. 2, a tilt hoop with guiding carriage from the front partly in section.

Fig. 3 is a side elevation of Fig. 2.

A U-shaped continuous rail *a*, preferably made of light metal, is employed as the track

for the guiding carriage of the tilt hoop. In the upper part *b* of the guiding carriage which forms one piece with the hoop foot *c*, the lower part *d* is guided with its hollow cylindrical part *e*. A spiral spring *f* presses the two parts apart and thereby presses the four guiding rollers *g* of the upper part and the two track rollers *h* of the lower part of the guiding carriage against the tracks on the rail *a*. The guiding rollers *g* and the track rollers *h* are mounted loosely on their journals without any special securing means. *m* is a tongue which prevents relative rotation of the two parts of the guiding carriage.

To two lateral eyes of the upper part of the guiding carriage are jointed two folding levers *i*, which connect the individual hoops together and fold the hood material when the roller hood is drawn together. The joints of the folding levers, which are connected together, are enclosed by hood protecting caps *k* in order to prevent damage to the material of the hood. *l* is the chain for opening and closing the hood.

What I claim is:

1. A device for guiding roller hoods comprising a guiding track, a second guiding track, a member guided upon the first guiding track, a member guided below the second guiding track connected with the hood, a recess in the second member, a projection on the first member adapted to slide vertically in the recess of the second member and helical spring in the recess adapted to press the two members apart and against their guiding tracks.

2. A device for guiding roller hoods comprising a guiding track, a second guiding track, a member guided upon the first guiding track, a member guided below the second guiding track connected with the hood, and displaceable in a vertical direction relative to the first member, resilient means adapted to force the members apart and against the guiding tracks and a tongue secured to one member and adapted to prevent a relative rotation of the two members.

3. A hood support for vehicles comprising a guide rail connected with the vehicle, said rail having overhanging portions, a hood

supporting hoop, a set of rollers resting on the rail and vertically movable relative to the hoop, a second set of rollers under said overhanging portions of the rail, a spring 5 interposed between the first set of rollers and hoop and upon which the hoop is supported to take up jolts, said spring also serving to urge the set of rollers apart whereby the two sets of rollers will yieldably engage 10 respectively the rail and overhanging portions.

4. A hood support for vehicles comprising a guide rail carried by the body of the vehicle, a hoop having a first set of rollers thereon, means on the rail to restrain them from upward movement, and a second set of rollers resting on the rail and movable towards and away from the first set, resilient means mounted between the second set of 15 rollers and hoop and operative to yieldably support the weight of the hoop on the second set of rollers to take up jolts and to yieldably hold the first set engaged with the rail.

5. A hood support for vehicles comprising a guide rail having upper and lower tracks, a carriage movable along the rail, two sets of guiding rollers on the carriage engaging respectively, the upper and lower tracks, a hood supporting hoop resting on 20 said carriage and spring means between an end of said hoop and the carriage and operative to resiliently support the hoop through one set of rollers on the lower track and take up jolts and also to hold the other 25 set of rollers against the upper track.

6. A device for guiding roller hoods of vehicles comprising a guide rail supported on the body of the vehicle, guide rollers normally resting on the floor of the rail, a hoop, and resilient means between the guiding rollers and the hoop such that the weight of 30 the hoop is transmitted through the resilient means onto the guiding rollers and thereby to the body of the vehicle, and a play between the hoop and the guiding rollers of 35 such size that it allows free up and down movement of the hoop against the action of the resilient means for taking up jolts arising between the body of the vehicle and 40 the hoop.

In testimony whereof I affix my signature.

FRITZ STEINECKE.
